UNITED STATES PATENT OFFICE.

JAMES R. CRAVATH, OF CHICAGO, ILLINOIS.

DESIGN FOR A REFLECTING-BOWL FOR INDIRECT-LIGHTING SYSTEMS.

48,309.

Specification for Design.

Patented Dec. 21, 1915.

Application filed July 22, 1915. Serial No. 41,400. Term of patent 7 years.

To all whom it may concern:

Be it known that I, JAMES R. CRAVATH, a citizen of the United States, residing at Chicago, in the county of Cook and State of Illinois, have invented a new, original, and ornamental Design for a Reflecting-Bowl for Indirect-Lighting Systems, of which the following is a specification, reference being had to the accompanying drawing, forming a part hereof.

My invention relates to an ornamental, artistic and attractive design for a reflecting bowl for indirect lighting systems.

In the drawings, Figure 1 is a vertical side elevation of my design for a reflecting bowl for indirect lighting fixtures. Fig. 2 is a top or plan view thereof; Fig. 3 is a vertical rear elevation of my design; and Fig. 4 is a vertical front elevation of my design.

Referring to the drawings which form a part of this specification, it will be seen that my design consists of a shell-like structure a portion whereof is of a semicircular shape and the remaining or front portion whereof comprises an elongated curved scoop-like bowl that extends a considerable distance in front of said hemispherical portion and the curvature of which is considerably flattened with respect to the aforesaid hemispherical portion and forms a continuation thereof along its bottom edge. The upper portion of the reflecting bowl is partly open while the remaining portion is closed as shown in Figs. 2 and 3 of the drawings,

and, as will be observed in Fig. 2, the outer edge of the forward portion describes a semi-circle, the ends of which emerge into and form a vertically disposed bead or rib that is disposed straight across the upper forward edge of the hemispherical portion.

The lower segment of the reflecting bowl is provided with an opening and adjacent the same and upon opposite sides thereof are disposed high-lights or poles from which a plurality of rays are arranged so as to radiate from said poles each comprising a graceful compound curve extending to the edge of the bowl. A portion of these rays meet at the rear of the hemispherical portion and form V-shaped flutings in the central rear portion thereof. Another portion of these rays meet on the under side of the forward member and provide similar V-shaped flutings. These flutings and the rays extend through the thickness of the reflector bowl and provide undulating portions upon the interior surface of the reflector bowl as shown in Fig. 2.

I claim:

The ornamental design for a reflecting bowl for indirect lighting systems, as shown and described.

Signed at Chicago, in the county of Cook and State of Illinois, this 16th day of July, 1915.

JAMES R. CRAVATH.

Witnesses:
